UNITED STATES PATENT OFFICE.

HENRY C. STIFF, OF JOHNSTOWN, PENNSYLVANIA.

FLANGeway GUARD.

Application filed August 11, 1925. Serial No. 49,558.

This invention relates to railway track structures and more particularly to flangeway guards for use at vehicular crossings and other points where it is customary to pave or otherwise fill the space between the track rails up to approximately the level of the top of the track.

One object of the present invention is to provide an improved form of flangeway guard having a removable head member which may be removed to permit free access to the base of the track rails for renewing or re-spiking the track rails without disturbing the paving between the rails.

Another object is to provide a novel form of guard having a head portion composed of a rolled shape and removably supported on a plurality of chairs which may be formed from cast steel, cast iron or malleable iron, thereby combining great strength with simple construction and a low cost of manufacture.

A further object is to provide a flangeway guard having the novel construction, design and combination of parts hereinafter described and illustrated in the accompanying drawings.

In the drawings—

Figure 1 is a plan view of a section of track embodying my invention.

Figure 2 is a transverse sectional elevation thereof and showing the paving between the rails.

Figure 3 is an enlarged transverse sectional elevation through one track rail and guard.

Figure 4 is a plan view of one of the chairs.

Figure 5 is an enlarged partial side elevation showing an end section of the flangeway guard.

Figure 6 is an enlarged transverse sectional elevation through a track rail and guard showing a slightly modified construction.

Figure 7 is a side elevation, and Figure 8 is a plan of the construction of Figure 6.

Referring more particularly to the drawings, the letter A designates the track structure as a whole, which is composed of the usual track rails 2, secured on the tiles 3 by

spikes 4. Flangeway guards B are secured along the rails 2, and asphalt or other paving material 5 is filled in between the flangeway guards B up to approximately the level 55 of the top face of the heads of the rails 2 to form a crossing.

Heretofore it has been customary to maintain the paving or filling in spaced away relation to the track rails by the use of wood planks, old rails laid on their sides, and other makeshift devices which cause horses to be thrown by catching the toe calks of their shoes in the grooves and under the head of track rails. All of these devices had 60 to be removed in order to renew or re-spike the track rails. The removal of the planks or other binding members allowed the paving to crumble and break, and also was a more or less laborious task.

The flangeway guards B of this invention are permanent structures especially designed for their particular use and need not be removed when renewing or re-spiking the track rails, and therefore, eliminate the disadvantages of the prior art and provide a generally improved construction.

The flangeway guards B are composed of a top or head member 7 and supporting chairs 8.

The chairs 8 are in the form of an integral casting and comprise a base portion 9 adapted to be supported on the track ties and to be secured in position by spikes 10 which pass through apertures 11 in the base 9, a body portion 12 having an undercut groove or slot 14 therein to receive a flange 15 of the head 7 having a locking head 16 along its free edge, and an integral supporting foot 17 projecting outwardly from the body portion 12. The foot 17 has its free end supported on the flange of the track rail and its upper face is adapted to engage and support the overhanging portion of the head of the guard.

The head portion as heretofore stated is preferably formed from a rolled shape and is provided with the flange 15 and head 16 along one longitudinal edge and with a groove 19 adjacent its other edge forming a flangeway and with an outwardly projecting flange or lip 20 along its other longi-

tudinal edge adapted to fit under the head of the track rail 2.

Suitable ears or lugs 22 may also be provided on the base portions 9 of the chairs 5 and suitable strips 23 of wood or metal (see Figures 3, 5, 6 and 7) may be secured between the lugs and extend from chair to chair to form abutments for the paving if desired.

In Figures 6, 7, and 8 I have shown a 10 slightly modified form of head 7 and chair 9 in which the body portion 12 of the chair is provided with a square horizontally undercut groove or slot 14^a adapted to receive a portion 16^a of the flangeway 15, which portion 15 16^a is bent at substantially right angles to the vertical portion of the flangeway 15. The portion 16^a is of a materially less vertical dimension than the undercut portion of the groove 14^a and is adapted to be locked in 20 position by a locking pin or wedge 25 which has a head 26 at one end adapted to engage the side wall of the chair and a split portion 27 at its other end. The split portion 27 is adapted to be spread or bent to lock 25 the pin in place.

If desired, in order to facilitate the removal of the head members 7, the head portion 16 may be cut away at a point adjacent each of the chairs 9 as indicated at 32, so 30 that the head members need only be moved longitudinally a comparatively short distance in order to release them from the chairs. When the cut away portions of the heads 16 register with the chairs the heads 35 may be freely lifted out of position.

The flangeway guards B are adapted to be made in comparatively short lengths of approximately six feet so that they may be conveniently used without bending on standard railway track curves, and all the sections 40 are of duplicate construction except the end sections.

The end sections have the end chair omitted and the head portion 7 is flattened out 45 and bent downwardly to form an inclined approach portion 29 which is provided with a spike aperture 30 to receive a rail spike 31 which is driven into a tie to hold the approach portion in position.

As stated before, it has heretofore been necessary to entirely remove the flangeway 50 guards of the prior art in order to renew or re-spike the track rails, while with the flangeway guards of this invention it is only necessary to remove the head portions 7 by 55 sliding the head portions longitudinally to permit free access to the base of the track rails for renewing or re-spiking the rails.

Therefore, the paving between the rails 60 is left undisturbed and much labor and expense are eliminated.

While I have shown and described certain specific embodiments of my invention, it will be understood that various modifications 65 will readily suggest themselves to those

skilled in the art and, therefore, I do not wish to be limited to the specific embodiments of my invention shown and described, since various modifications may be made without departing from the scope of my invention as defined in the appended claims.

I claim:

1. In a track structure the combination with a track rail, of a flangeway guard having a rigid supporting portion secured to the ties of the track structure and a head portion slidably mounted in a recess in said supporting portion and detachable therefrom so as to permit ready access for renewing and spiking the track rails.

2. In a track structure, the combination with a track rail, of a flangeway guard comprising a plurality of supporting chairs secured to the ties of the track structure, said chairs each being provided with a recess extending downwardly from the upper face of the chair and having its lower end undercut and enlarged, and a rolled steel head portion having a flangeway groove adjacent one longitudinal edge and an offset head 90 along its opposite longitudinal edge adapted to be engaged in the undercut and enlarged portion of said recesses in said chairs, and means for supporting the overhanging portion of said head.

3. In a track structure the combination with a track rail, of a flangeway guard comprising a plurality of supporting chairs secured to the ties of the track structure, said chairs each being provided with an inwardly enlarged recess extending downwardly from the upper face of the chair, and a rolled steel head portion having a flangeway groove adjacent one longitudinal edge and an enlarged head along its opposite longitudinal edge adapted to be engaged in said recesses in said chairs, and means formed integral with said chairs for supporting the overhanging portion of said head.

4. In a track structure the combination with a track rail, of a flangeway guard comprising a plurality of supporting chairs secured to the ties of the track structure, said chairs each being provided with an inwardly enlarged recess extending downwardly from the upper face of the chair, a rolled steel head portion having an enlarged rounded head along its opposite longitudinal edge adapted to be engaged in said recesses in said chairs, means for supporting the overhanging portion of said head, and means extending between said chairs for closing the space between said head and the track bed.

5. In a track structure the combination with a track rail, of a flangeway guard comprising a plurality of supporting chairs secured to the ties of the track structure, said chairs each being provided with an inward-

ly enlarged recess extending downwardly from the upper face of the chair, a rolled steel head portion having an enlarged rounded head along its opposite longitudinal edge adapted to be engaged in said recesses in said chairs, means for supporting the overhanging portion of said head,

and means removably mounted between said chairs for closing the space between said head and the track bed.

19

In testimony whereof, I have hereunto set my hand.

HENRY C. STIFF.
